(57) **CLAIM**

The ornamental design for a leg support stand, as shown and described.

DESCRIPTION

FIG. 1 is a perspective view of a leg support stand, showing our new design;

FIG. 2 is another perspective view thereof;

FIG. 3 is a top plan view thereof;

FIG. 4 is a bottom plan view thereof;

FIG. 5 is a front plan view thereof;

FIG. 6 is a rear plan view thereof;

FIG. 7 is a left side elevation view thereof, with the right side elevation being a mirror image thereof;

FIG. 8 is a cross-sectional view of line 8-8 taken from FIG. 3 thereof; and,

FIG. 9 is another perspective view thereof, showing the leg support stand in environment.

The broken lines illustrate the environment and do not form part of the claimed design.
